ATTORNEY

UNITED STATES PATENT OFFICE

JOSEPH SOSS, OF BROOKLYN, NEW YORK

HINGE

Application filed October 8, 1927. Serial No. 224,852.

This invention relates to hinges and particularly to what are known as covered joint hinges; and the object of the invention is to provide a hinge of the class specified, one of the butts of which is fashioned from a single piece of sheet metal, the central portion of which is apertured and folded or fashioned to form the pintle bearing portion of the butt, and a hood partially encircling said pintle bearing portion to conceal or partially conceal the joint of the hinge; a further object being to provide a hinge butt of the class specified, wherein the sheet of metal from which said butt is formed is folded upon itself, a number of times, to provide a multiple wall for the pintle bearing or bearings of the hinge butt to produce strong and durable bearings; a further object being to so construct the butt of the hinge and especially the pintle bearing portion thereof as to maintain said bearings against separation when subjected to stress or strain, and to produce a butt having a neat and finished appearance, and one which can be produced at nominal cost; and with these and other objects in view, the invention consists in a hinge of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of one form of hinge made according to my invention.

Fig. 2 is a section on the line 2—2 of Fig. 1. Fig. 3 is a section on the line 3—3 of Fig. 1 of one butt only of the hinge.

Fig. 4 is a view similar to Fig. 3 but showing a modification.

Fig. 5 is a view similar to Fig. 2 but showing only one butt of the hinge and showing a modification.

Fig. 6 is a view similar to Fig. 5 but showing a section through another area of the butt; and,

Fig. 7 is a sectional, detail view showing the first step in the formation of one of my improved hinge butts.

In practice, I employ two hinge butts 10 and 11, the butt 11 being of any conventional form and consisting in the construction shown, of a single sheet of metal, fashioned centrally to form circular pintle bearings 12 and intermediate recesses 13 for receiving the pintle bearings of the butt 10. The sides of the sheet of metal from which the butt 11 is formed are brought together and secured to form an attaching plate portion 14.

The butt 10, as shown in Figs. 1 to 3 inclusive, is fashioned from a single sheet of metal, the central portion of which is provided with spaced apertures which form intermediate the pintle bearings of said butt when completed, recesses 15 for receiving the pintle bearings 12 of the butt 11. The central apertured portion of the sheet of metal from which the butt 10 is formed is folded or otherwise fashioned to form spaced, circular pintle bearings 16, having as seen in Fig. 2 of the drawing, three outer wall members 17, 18 and 19 and one inner wall member 20. In forming the hinge butt 10, the sheet of metal is first folded in the manner seen in Fig. 7 of the drawing, so as to bring the three walls 17, 18 and 19 one upon the other. When in this position, said walls may be welded or otherwise secured together, after which the side portion 10^a of the sheet, including the three walls 17, 18 and 19 are curled or otherwise fashioned around a pin or mandrel to form of the side 10^a, the single wall 20, and the side 10^a is brought upon the side 10^b and may be secured thereto by riveting, welding, or otherwise, especially at the point 21, note Fig. 2, to prevent the opening of the pintle bearing 16.

It will be noted on a consideration of Figs. 2 and 3 of the drawing, that the fold of the sheet from which the butt 10 is formed, intermediate the walls 17 and 18 as at 22, is arranged adjacent the flat part 23 of the wall 20 where it joins the attaching plate portion of the butt. The fold intermediate the walls 18 and 19 as at 24, forms a projecting stop shoulder for limiting the relative movement

of the butts 10 and 11 in one direction, and this stop shoulder also constitutes the end of the hood portion which is formed by the outer wall 19, and extends longitudinally of the hinge.

5 Where the apertures 15 are located in the sheet, these apertures extend through the walls 17, 18 and 20 as clearly seen in Fig. 3 of the drawing, thus leaving a single outer wall or hood 19^a which is a continuation of the wall 19. With this construction, sufficient clearance is provided between the bearings 12 and the hood portion 19^a to prevent the marring of the finish that may be applied to the bearings 12. But, in Fig. 4 of the drawing, I have shown in addition to the wall 19^a, a hood portion including an extension of the wall 18 as at 18^a, which result is accomplished by simply shortening the dimensions of the 10 apertures in the sheet from which the butt is formed, to provide for the recesses to receive the bearings 12 of the butt 11. Aside from this modification, the structure shown in Fig. 15 4 is identical with that shown in Figs. 1 to 3 inclusive.

20 In Figs. 5 and 6 of the drawing, I have shown another modification wherein the butt 10 is formed in precisely the same manner as shown in Figs. 1 to 3 inclusive, with the exception that the overlapping walls 17, 18 and 19 are extended or overlapped to a greater degree to provide a three wall thickness, entirely encircling the pintle pin at the pintle bearing portions of the butt. In these figures, 25 represents the hinge butt, 26 the wall similar to the wall 17, 27 the wall similar to the wall 18, and 28 corresponds to the wall 19; 29 is the fold in the sheet of metal from which the butt 25 is formed similar to the 25 fold 22, 30 the fold similar to the fold 24, and 31 the fold similar to the fold 23. In other words, by extending the overlapping portions of the walls as described, the stop 24 as seen in Figs. 2 and 3 has been extended 40 around to the fold 31, and the three walls 26, 27 and 28 entirely encircle the pintle pin 32.

45 In forming the hinge butt shown in Figs. 5 and 6, it will be understood that the overlapping portions, forming the walls 26, 27 and 28 are folded or otherwise fashioned around a pin or mandrel to form the pintle bearings of the butt, and the side portions 25^a and 25^b are brought together and welded or otherwise secured to form the complete butt. In 50 this construction, the apertures in the sheet from which the butt 25 is formed, will be cut out in such manner as to leave a single wall 28^a in the recesses of the butt to receive the pintle bearings of the other butt of the hinge, 55 said wall forming the hood portion which terminates at 33 to form a stop shoulder as clearly seen in Fig. 6 of the drawing. It will be understood that a hinge butt made in the manner above set out, and as disclosed in the 60 several figures of the drawing, may be pro-

duced at a comparatively nominal cost and from comparatively thin sheet metal, depending upon the specific use for which the hinge is intended. At the same time, a strong and durable hinge is produced, and one which 70 will have a neat and finished appearance, the joint of the hinge being covered or concealed by the hood portion which extends from the attaching plate portion of the butt in a smooth, curved line.

75 In the construction shown in Figs. 5 and 6 of the drawing, it will be understood that the folded corner 30 may be forcibly fixed within the fold 31 to retain the pintle bearings against separation when subjected to stress or strain. As previously stated, the several parts or sheets which may be regarded as dimensions, may be secured together, which aids in giving strength, rigidity, and durability to the finished product. As a matter 80 of fact, the distinctive feature of the invention resides in the construction of the pintle bearing portion of the butt of a laminated body, giving to such pintle bearing portion, the required dimensions as well as strength 85 and durability, and it will be understood that the pintle bearing, as well as the attaching plate portion of the butt, may be offset in the usual or in any desired manner to compensate the hinge to supports and to the hanging of doors of any kind or class.

90 It will be understood that while I have described a certain method of forming or constructing the hinge butt, that I am not necessarily limited to the specific arrangement of the walls of the pintle bearing portions of the butt herein described, and various other changes in and modifications of the construction herein set out may be made within the scope of the appended claims, without departing from the spirit of my invention or sacrificing its advantages.

95 Having fully described my invention, what I claim as new and desire to secure by Letters Patent, is:—

100 1. A hinge butt fashioned from a single sheet of metal, the central portion of said sheet being provided with spaced apertures and being folded upon itself a number of times to form a multiple wall thickness, said 105 walls being secured together, and that part of the sheet with the multiple walls therein being fashioned to form a curved hood portion with spaced cylindrical pintle bearings within said hood portion formed intermediate the apertures in said sheet.

110 2. A hinge butt, the pintle bearing portion of which is fashioned to form a hood member 115 extending longitudinally of the butt and composed of three walls arranged one upon the other and secured together, and the pintle bearings of the butt being formed by a wall extending from the hood portion, said last 120 named extended wall and another wall of the 125

hood portion extending in parallel relation to form an attaching plate portion.

3. A hinge butt, the pintle bearing portion of which is fashioned to form a hood member extending longitudinally of the butt and composed of three walls arranged one upon the other and secured together, and the pintle bearings of the butt being formed by a wall extending from the hood portion, said last named extended wall and another wall of the hood portion extending in parallel relation to form an attaching plate portion, and the walls of the hood portion intermediate the pintle bearings being cut away to receive the other butt of the hinge.

4. A sheet metal hinge butt fashioned from a sheet metal body having a laminated portion, the laminated portion of said body being fashioned to form a curved hood portion, spaced pintle bearings within and partially formed by said hood portion, and the laminations of the hood portion intermediate the pintle bearings being reduced.

5. A hinge butt fashioned from a sheet of metal, the central portion of said sheet being folded upon itself to form a laminated portion, the walls of which are secured together, said laminated portion being fashioned to form a curved hood portion with spaced cylindrical bearings within said hood portion, and said sheet including the laminated portion being apertured to form, intermediate said bearings, spaces for receiving bearings of the other butt of the hinge, and the walls of the hood portion intermediate the bearings being of less thickness than where said bearings are located.

6. A hinge butt of the class described fashioned from sheet metal, the attaching plate part of said butt consisting of two sheets, one side of the outer sheet being curved and folded upon itself a number of times to form a hood portion extending longitudinally of said side of the butt to conceal the joint of the hinge and said sheet extending to form in conjunction with said hood portion a circular pintle bearing within said hood and joining the inner sheet of the attaching plate adjacent said bearing.

7. A hinge butt of the class described fashioned from sheet metal, the attaching plate part of said butt consisting of two sheets, one side of the outer sheet being curved and folded upon itself a number of times to form a hood portion extending longitudinally of said side of the butt to conceal the joint of the hinge, said sheet extending to form a circular pintle bearing within said hood and joining the inner sheet of the attaching plate adjacent said bearing and the wall thickness of the hood portion at one side of said bearing being reduced to receive the pintle bearing of the other butt of the hinge.

8. A covered joint hinge butt of the class described fashioned from a sheet metal body

folded to form a laminated portion, the laminated portion of said body being fashioned into cylindrical formation to provide a longitudinal curved hood portion and spaced pintle bearings of multiple wall thickness arranged at spaced intervals within said hood portion.

9. A covered joint hinge butt of the class described fashioned from a sheet metal body folded to form a laminated portion, the laminated portion of said body being fashioned into cylindrical formation to provide a longitudinal curved hood portion and spaced pintle bearings of multiple wall thickness arranged at spaced intervals within said hood portion and the laminated portion intermediate the bearings being of less wall thickness than where said bearings are located.

In testimony that I claim the foregoing as my invention I have signed my name this 29th day of September, 1927.

JOSEPH SOSS.
